UNITED STATES PATENT OFFICE.

HARRY E. CAMPBELL, OF MILWAUKEE, WISCONSIN, ASSIGNOR TO UNION ELECTRIC MANUFACTURING COMPANY, OF MILWAUKEE, WISCONSIN, A CORPORATION OF WISCONSIN.

ELECTRIC SWITCH.

Application filed January 18, 1924. Serial No. 687,073.

To all whom it may concern:

Be it known that I, HARRY E. CAMPBELL, a citizen of the United States, and resident of Milwaukee, in the county of Milwaukee and 5 State of Wisconsin, have invented new and useful Improvements in Electric Switches, of which the following is a description, reference being had to the accompanying drawings, which are a part of this specification.

This invention relates to improvements in electric switches more particularly, although not solely adapted for drum type switches.

15 It is one of the objects of the present invention to provide an electric switch which is of very compact form to permit a number of the switches to be closely mounted together in a drum switch, and also permit the independent removal of said switches for repairs or replacement without disturbing adjacent switches.

20 A further object of the invention is to provide an electric switch member having a yielding engagement with a movable member in which the contact portion of the switch member may be easily removed for replacement.

25 A further object of the invention is to provide an electric switch having a novel spring means for yieldingly holding the contact portion in position which may be easily disengaged to permit the said contact portion to be swung to a visible position for cleaning or repairing, without disturbing the adjacent switch members.

30 A further object of the invention is to provide an electric switch formed almost entirely of stamped or commercial metal which 35 is of simple construction is strong and durable and which will secure a good electrical contact with its cooperative contact members.

With the above and other objects in view 40 the invention consists of the improved electric switch and its parts and combinations as set forth in the claims, and all equivalents thereof.

In the accompanying drawing in which 45 the same reference characters indicate the same parts in all of the views:

50 Fig. 1 is a side view of the improved switch with parts shown in section;

Fig. 2 is a top view of the contact finger; 55 Fig. 3 is a sectional view taken on line 3—3 of Fig. 1 of the contact finger removed from its support;

Fig. 4 is a similar view taken on line 4—4 of Fig. 1;

Fig. 5 is a side detail view; 60

Fig. 6 is a sectional detail view thereof;

Fig. 7 is a detail view of the end portion of the fingers; and

Fig. 8 is a similar view of the finger pivotal connection. 65

As the invention is particularly applicable to drum controllers the electric switch is shown as forming part thereof but it is to be understood that the switch may be used for other types of switches. Referring to 70 the drawing the numeral 8 indicates a rotary drum upon which is mounted a segmental contact 9 positioned to engage the improved contact finger 10. The drums of the drum controllers are usually provided with a plurality of segmental contacts, and one or more elongated holders 11 have contact fingers mounted thereon which engage the respective drum contacts. 75

As the contact fingers are all alike only 80 one is shown with its coacting segmental contact.

The finger holder 11 is formed of commercial angle iron secured to a support in any manner desired and the edge portions of the 85 holder are covered by strips of insulating material 12 to insulate the contact finger bracket 13 therefrom and from each other. The said bracket 13 is formed of commercial strip metal bent into angular shape to form 90 a hook part 14 which extends around one edge portion of the holder, and is also bent at right angles at another portion to form a shoulder 15 to engage the opposite edge of the holder 11. The said bracket is then 95 bent at right angles at 16 to extend away from the holder and the end portion is again bent at right angles to form a stop shoulder 17 for holding one end of the clamping member 18. The opposite end 18' of the clamping member is rounded and bears against a portion of one of the insulating strips 12 medially of the holder 11. A bolt 19 extending through the bracket and medially through the clamping member and having 100 a nut 19' threaded on its end draws the two 105

parts together to clamp the holding member therebetween and adjustably lock the bracket to the holding member.

The opposite end portion 13' of the bracket extends in a straight line and has a fulcrum strip 20 riveted thereto which is formed with upwardly curved portions 21 and 22 and a stop portion 23. The portions 21 are bifurcated or spaced apart as shown in Fig. 8. The curved portions 21 and 22 in connection with the bracket 13 form fulcrum openings or eyes and in the opening formed by the part 22 a rectangular split ring 23 is pivoted, and a lever arm 24 extending through the ring is provided with transversely extending side slots 24' through which the curved end portions 21 extend to pivot the lever arm to the bracket. The said curved portions 21 are spaced apart to receive the slotted portions of the arm 24 therebetween and to permit the portions 21 to extend through the side slots. A flexible braided circuit wire 25 rests on top of the lever arm 24 and extends therefrom and around the hooked portion 14 of the bracket and is connected to a medial portion of the bracket by a screw 26 which also extends through the terminal 27 of a circuit lead wire 28 connected thereto. A contact finger 29 is mounted on the free end portion of the lever arm and is connected thereto by a screw 30 which also binds the outer end of the circuit wire 25 between the lever arm and the contact finger 29. The outer end portion 31 of the lever arm 24 is reduced in cross sectional size and bent outwardly to extend through the opening 32 in the contact finger 24 to prevent said finger from turning on the screw 30. The outer end portion of the contact arm is formed with an enlargement 29' on its inner end which is of rounded formation and bears against the rotary segment 9 to form an electrical connection therebetween. A stop screw 33 threaded through the contact finger 29 bears against the stop portion 23 of the fulcrum strip 20 to limit the inward movement of said finger 29 when disengaged from the rotary contact 9. A spring clip 34 engages the squared head 33' of the stop screw 33 and holds said screw in adjusted position. To maintain the contact finger yieldingly in position a U-shaped spring 34' is positioned between the lever arm 24 and the outer portion of the rectangular ring 23. The inner portion of the spring is of greater length than the outer while the outer end portion is formed with a hook like part 35 which engages the outer portion of the rectangular ring 23. The tension of the spring and its shape holds the parts in position and the contact finger in yielding engagement with the segment and if it is desired to smooth off the face of the finger it is only necessary to disengage the spring from

the ring and swing the ring to the right and then the lever arm and the finger may be swung outwardly away from the segmental contact and expose the working face of the finger for cleaning. If it is desired to replace the finger it is only necessary to remove the screw 30 and the replacement may be easily made.

As the side edge portions of the fingers extend approximately in straight lines a plurality of the fingers may be placed in parallel spaced relation quite close together and any one of the fingers repaired or replaced without disturbing the others.

From the foregoing description it will be seen that the electric switch is of simple construction, is strong and durable and is well adapted for the purpose described.

What I claim as my invention is:

1. In an electric switch, in combination, a support, a finger bracket mounted thereon and having an eyed portion extending in a plane parallel to the engaged portion of the bracket, a lever arm pivotally connected to the eyed portion, a ring pivotally connected to the finger bracket and extending around the lever arm, a contact finger connected to the lever arm and projecting outwardly therefrom, and a spring means interposed between the lever arm and a portion of the ring for yieldingly holding the contact finger in position.

2. In an electric switch, in combination, a support, a finger bracket mounted thereon and having eyed portions extending in a plane parallel to the engaged portion of the bracket, a ring pivotally connected to one of the eyed portions, a lever arm pivotally extending through the other eyed portion and also through the ring, a contact finger connected to the lever arm and projecting outwardly therefrom, a spring means interposed between the lever arm and a portion of the ring for yieldingly holding the contact finger in its inner position, and means for limiting the inner movement of said contact finger.

3. In an electric switch, in combination, a support, a finger bracket mounted thereon, a fulcrum forming part of the finger bracket and providing two eyes in connection therewith, a ring pivotally extending through one of the eyes, a lever arm pivotally connected to the other eyed portion and extending through the ring, a contact finger connected to the lever arm and projecting outwardly therefrom, a spring means interposed between the lever arm and a portion of the ring for yieldingly holding the contact finger in its inner position, a flexible circuit means connecting the contact finger to the finger bracket part, and means for limiting the inner movement of said contact finger.

4. In an electric switch, in combination, a support, an angular finger bracket mounted

- thereon, a fulcrum strip forming part of the finger bracket and providing two eyes in connection therewith, a rectangular ring pivotally extending through one of the eyes, 5 a lever arm pivotally connected to the other eyed portion and extending through the ring, a contact finger mounted on the lever arm and projecting outwardly therefrom and having a contact head formed thereon, a fulcrum strip part for limiting the inward movement of said contact finger. 40
6. An electric switch, comprising a support formed of angled metal having its edge portions covered with an insulating material, an angular finger bracket extending 45 around said edge portions, and projecting outwardly therefrom, a clamping member engaging one side portion of the insulating material and an angled portion of the bracket, a screw extending through the clamping 50 member and the bracket for clamping the support therebetween, a fulcrum strip forming part of the bracket and providing inner eye portions and a medial eye and a stop portion, a rectangular ring pivotally connected to the medial eye and projecting upwardly therefrom, a lever arm having transverse side slots at its inner end through which the inner eyed portions of the fulcrum member extend, said lever arm extending 60 through the ring and having an angularly projecting end portion, a contact finger mounted on the lever arm and having an opening into which the angular end portion extends and also having an enlargement on 65 its outer end, a flexible circuit means connected to the contact finger, a U-shaped spring bearing on the circuit means and having a hook shaped end portion which removably bears against the outer portion of 70 the ring for yieldingly holding the contact finger in its inner position, and a stop screw extending through the contact finger and engaging the stop portion of the fulcrum strip part for limiting the inward movement 75 of said contact finger.
5. In an electric switch, in combination, an angular support, an angular finger bracket having portions which hook around said support, a clamping member associated with said bracket to connect the same to said support, a fulcrum strip forming part of said bracket and providing two eyes in connection with the bracket, a rectangular ring pivotally connected to one eye, a lever arm pivotally connected to the other eyed portion and extending through the ring, a contact finger mounted on the lever arm and projecting outwardly therefrom and having a contact head formed on its outer end, a U-shaped spring removably interposed between a portion of the ring and the lever arm for yieldingly holding the contact finger in its inner position, a flexible circuit means connecting the contact finger to the finger bracket, a cable terminal connected to the circuit means, and a stop screw extending through the contact finger and engaging the stop portion of the fulcrum strip part for limiting the inward movement of said contact finger. 60
